UNITED STATES PATENT OFFICE.

WILLIAM A. IRWIN AND EDWARD S. SCHWARTZ, OF NEW YORK, N. Y.

HEADLIGHT.

Application filed December 15, 1924. Serial No. 756,026.

To all whom it may concern:

Be it known that we, WILLIAM A. IRWIN and EDWARD S. SCHWARTZ, both citizens of the United States, and residents of the city 5 of New York, borough of Bronx, in the county of Bronx and State of New York, have invented a new and Improved Headlight, of which the following is a full, clear, and exact description.

10 This invention has relation to headlights and has particular reference to an improvement in headlights which are especially designed for automobiles or other motor vehicles.

15 One of the outstanding objects of the present invention is to provide an improved headlight in which the lighting unit is adjustable within the casing or housing, whereby the proper focusing of the light rays is 20 accomplished.

The invention furthermore comprehends a means forming part of the lighting unit which functions to eliminate the glare from the headlight upon the eyes of the drivers 25 of approaching vehicles, pedestrians or other persons in the path of movement of the vehicle while producing upon the roadway sufficient illumination.

As a further object, the invention contemplates an improved headlight structure in 30 which the lighting unit is capable of being readily removed from and applied to the casing or housing.

The invention furthermore comprehends 35 an improved headlight structure which is comparatively simple in its construction, inexpensive to manufacture and which is highly efficient in its purpose.

With the above recited and other objects 40 in view, the invention resides in the novel construction set forth in the following specification particularly pointed out in the appended claim and illustrated in the accompanying drawings, it being understood that 45 the right is reserved to embodiments other than those actually illustrated herein, to the full extent indicated by the general meaning of the terms in which the claim is expressed.

50 In the drawings—

Figure 1 is a vertical longitudinal sectional view through a headlight constructed in accordance with the invention.

55 Figure 2 is a horizontal longitudinal sectional view taken approximately on the line indicated at 2—2 in Figure 1.

Figure 3 is a fragmentary perspective view of the adjustable glare shield or deflector.

Figure 4 is a fragmentary perspective 60 view of the lighting unit mounting and supporting means.

Referring to the drawings by characters of reference, 10 designates a substantially cylindrical casing or housing, to the forward 65 open end of which the usual lens frame 11 is attached carrying the lens 12, and to the rear open end of which a closure member 13 is attached. Within the housing or casing 10 a lighting unit is supported, and the said 70 lighting unit consists of a parabolic reflector 14 which is provided with a central apertured bearing 15, the apertured portion of which is threaded to receive the threaded tubular shank 16 of a lamp socket 17 within 75 which the lamp 18 is mounted. By rotating the lamp socket, the threaded shank 16 effects forward and rearward axial adjustments of the lamp, and binding nuts 19 serve to maintain the lamp in its axially adjusted 80 relation to the reflector.

The means for supporting the lighting unit whereby the same is vertically slidable and vertically and horizontally swingable with respect to the casing or housing, comprises a supporting rod 20 which is vertically mounted within the rear open end of the casing, preferably by engaging the threaded lower end 21 in a threaded boss 22 formed adjacent the lower 85 end of the housing. The opposite end of the rod 20 is introduced through an inwardly bossed opening 23 in the upper portion of the housing, and the upper end of the rod is provided with a kerf 24 whereby the 90 threading or unthreading of the end 21 may be accomplished. An apertured slide 25 is mounted for vertical sliding movement on the supporting rod 20, and is maintained against movement by a set screw 26. The 95 slide is provided with forwardly projecting spaced parallel ears 27 which are provided with transverse aligned apertures. The reflector 14 has secured thereto a bracket 28 having a rearwardly projecting apertured lug 100 105 29 which is received between the ears 27 with its apertured portion aligned with the apertures in the ears 27. A transverse volt 30 110 is passed through said aligned apertures and receives a wing nut 31. Under this arrangement, it will be seen that by loosening the wing nut 31 the reflector may be swung verti-

cally with respect to the slide 25, so that the reflector is vertically swingable. When the desired adjustment is obtained, the wing nut is tightened to hold the reflector against 5 swinging movement. When the set screw 26 is loosened, the slide 25, which supports a reflector, may be raised or lowered therewith or the slide may be swung horizontally so that the reflector is horizontally swing- 10 able within the casing. When the set screw is tightened, the slide is maintained against turning or sliding movement to hold the lighting unit and reflector in adjusted position.

15 In order to provide means for shielding the eyes of the drivers of approaching vehicles or other persons from the direct glare, a shield or deflector blade 32 is provided which is secured to a transversely disposed 20 rod or shaft 33. The rod or shaft is mounted in bearings 34 carried by the forward end of the reflector 14 at approximately diametrically opposite points. The bearings are disposed slightly above the center 25 of the reflector, as clearly illustrated in Figure 1 of the drawings. The rod or shaft 33 is provided with a rearwardly directed terminal 35 disposed exteriorly of the reflector 14, and a detent member 36 is secured 30 to the outer side of the reflector and formed with a plurality of notches 37 into which the free end of the terminal 35 is selectively sprung due to its inherent resiliency. The

rear medial portion of the deflector blade 32 projects rearwardly in a substantially arcuate formation as illustrated in 38 so that the proper intersection of the light rays is accomplished to shield the eyes of persons in the path of the headlight from the glare. This arrangement admits of proper adjustment of the shield or deflector blade 32 and when properly adjusted in combination with the adjustments of the lamp and reflector in the housing or casing admits of the proper illumination of the road in advance of the 45 vehicle while preventing glare.

Having thus described our invention, we claim:

The combination with a headlight casing and a reflector of the beam projecting type mounted therein, of approximately diametrically opposed bearing brackets mounted on the forward edge of said reflector, a horizontal rod journaled in said brackets, a glare shield carried by the rod, a rearwardly and inwardly bent crank arm carried by one end of the rod, and a vertically disposed plate mounted on the outside of the reflector having a series of notches in its edge to accommodate the free end 55 of the crank arm, whereby the glare shield may be selectively tilted and locked in various positions of adjustment.

WILLIAM A. IRWIN.
EDWARD S. SCHWARTZ.
